DESIGN FOR A VEHICLE TIRE

George W. Anderson, Akron, Ohio, assignor to
The General Tire & Rubber Company, Akron,
Ohio, a corporation of Ohio

Application October 25, 1934, Serial No. 53,764

Term of patent 14 years

To all whom it may concern:

Be it known that I, George W. Anderson, a citizen of the United States, residing at Akron, in the county of Summit, State of Ohio, have invented a new, original, and ornamental Design for a Vehicle Tire, of which the following is a specification, reference being had to the accompanying drawing, forming a part thereof.

Fig. 1 is a side elevational view of a vehicle

tire with side wall portions in full lines, showing my new design;

Fig. 2 is a cross-sectional view taken on line 2—2 of Fig. 1 with side wall portions in full lines.

I claim:

The ornamental design for a vehicle tire, as shown.

GEORGE W. ANDERSON.
